DETACHABLE HEEL

Arthur Fisk, New York, N. Y., assignor of one-half
to Bradley Mahler, Detroit, Mich.

Application October 17, 1944, Serial No. 558,982

1 Claim. (Cl. 36—36)

2

1
This invention relates to detachable treads for heels.

One of the objects of my invention is to provide a tread member for heels which can readily be replaced without the employment of a skilled artisan for such replacement.

Another object is the provision of a tread member for heels which is interchangeable between the right and left shoes, thereby rendering it possible to equalize the normally unequal wear of heel tread members.

A further object is the provision of a tread member for heels which carries no metal fastening devices such as nails which can protrude through the wearing surface of the tread member when the latter is worn down.

Other objects will become apparent from a reading of the specification.

Two preferred embodiments of the invention are illustrated in the accompanying drawing in which—

Fig. 1 is a longitudinal vertical section of the first of said embodiments;

Fig. 2 is a horizontal section thereof on the line 2—2 of Fig. 1;

Fig. 3 is a longitudinal vertical section of the tread member of the said embodiment;

Fig. 4 is a horizontal section of the second of said embodiments on the line 4—4 of Fig. 5; and

Fig. 5 is a longitudinal vertical section of said second embodiment.

Referring now to Figs. 1 to 3 inclusive, the heel construction includes a fixed heel member 10 and a detachable tread member 11. A recess 12 of substantially the same shape as the heel, is formed in the bottom of the heel. Affixed in said recess by means of screws 13 is a clamp 14 which conforms to said recess in shape and dimensions. The clamp is provided with vertically slotted, contractible walls 15 which are turned back upon themselves to form a hollow peripheral bead 16. A draw-in wire 17 having hooked free ends is carried by said bead. A cam-faced lever 18 engages said hooked ends and draws them together thereby causing contraction of the clamp walls.

The detachable tread member 11 comprises a tread proper 20 having a raised upper portion 21 which conforms in shape and dimensions to the space defined by the inner walls of said clamp, said clamp being adapted to accommo-

date and tightly hold said raised portion. A recess 22 in the concave wall of said tread portion 20 receives lever 18 when the latter is in depressed or engaging position.

5 The clamp performs two functions in this construction: by virtue of its gripping pressure it holds tread member 11 snugly against heel member 10, and by virtue of its rounded but non-circular shape it prevents rotary movement of 10 said tread member about its vertical axis.

The embodiment shown in Figs. 4 and 5 is identical with the first embodiment except in two respects: The recess 25, clamp 26 and raised portion 27 are circular rather than non-circular in shape, and a plurality of inwardly projecting lugs or teeth 28 on the side walls of the clamp enter correspondingly shaped and spaced recesses 29 in the side of raised portion 27. In this embodiment, these teeth prevent rotary 20 movement of the tread member relative to the heel.

It will be appreciated that the constructions thus described are but preferred embodiments of the invention and that modifications thereof may 25 be had without departure from the basic principles of the invention.

For example, the clamp may be provided with other non-circular shapes. The particular shape is not important as long as it is non-circular 30 and without sharp corners around which it would be difficult to draw wire 17. The construction may be reversed without any violence whatsoever to the principles of the invention by affixing the clamp to the tread member and 35 providing the heel member with a downwardly projecting portion which the clamp would be adapted to receive. The device may be made an integral part of the shoe at the factory or it may be attached to ordinary shoes by the ultimate consumer, as a worn tread replacement.

I claim:

A heel construction comprising a fixed heel member and a detachable tread member, said heel having a recess in the bottom thereof and 45 a circular contractable clamp in said recess, said tread having a raised circular upper portion which said clamp is adapted to engage, said clamp being provided with inner teeth which engage correspondingly spaced and dimensioned 50 recesses formed in said raised circular portion.

ARTHUR FISK.
